UNITED STATES PATENT OFFICE.

GEORGE S. ROBERTS, OF BEND, OREGON.

STEAM-BOILER AND STEAM-POWER GENERATION.

1,398,395.

Specification of Letters Patent. Patented Nov. 29, 1921.

Application filed April 21, 1921. Serial No. 463,212.

To all whom it may concern:

Be it known that I, GEORGE S. ROBERTS, a citizen of the United States, residing at Bend, in the county of Deschutes and the State of Oregon, have invented certain new and useful Improvements in Steam-Boilers and Steam-Power Generation; and I do hereby declare that the following is a full, clear, and exact description of the invention, such as will enable others skilled in the art to which it appertains to make and use the same.

The present invention has reference to improvements in steam boilers of those types employed in heating-plants, locomotives, motor-driven vehicles, power-boats, stationary power-plants, etc., having for an object to provide a boiler for effecting the rapid generation of steam with the use of a greatly reduced heating area and without a material portion of water such as used by the now prevalent above mentioned types of boilers.

It is also an object of the invention to provide a boiler having means in form of percolating devices for circulating the water as it is heated and directing the same onto superheated surfaces in order that such water will be rapidly converted into steam.

Another novel characteristic of the invention may be stated to reside in the provision of baffles, so disposed with relation to the fire-tubes of a boiler as to effect the distribution of fine streams or jets of water evenly or uniformly thereover and further, the positive reduction of the water to steam for delivery to the boiler dome.

Other objects will be in part obvious and in part pointed out hereinafter.

In order that the invention and its mode of operation may be readily understood by persons skilled in the art, I have in the accompanying illustrative drawings and in the detailed following description based thereon set out a practical embodiment of the same.

In these drawings:

Figure 1 is a vertical longitudinal section therethrough a boiler equipped with my invention; Fig. 2 is a vertical transverse section therethrough, and Fig. 3 is an enlarged detail in section of one of the percolating devices and fragments of the baffles.

Having more particular reference to the drawings, in connection with which like characters of reference will designate corresponding parts throughout the several

views, 1 indicates in its entirety, a boiler, having a fire-box provided with the usual crown-sheet 2 in the lower portion thereof, as clearly shown in the Fig. 2, and also, with a plurality of spaced superposed rows of horizontally arranged fire-tubes 3.

Arranged upon the upper portion of the crown-sheet 2 are a plurality of circulating or percolating devices which are indicated for the purpose of convenience by the reference characters 4 and 5, said devices consisting, as shown in the Fig. 3, of elongated tubular members having enlarged hollow base portions 6 provided about their lower extremities with circularly disposed openings 7, the purpose of which will be hereinafter apparent. The base portion 6 of the percolating devices 4 and 5 are preferably rigidly secured in juxtaposed relation upon the convex side of the crown-sheet 2, as by bolts or other suitable fastening devices, not shown, and the elongated tubular portions thereof extend upwardly between the horizontal fire-tubes 3 to points in proximity to the top of the casing of the boiler 1. In this connection, it is to be noted that the percolating devices 4 are of substantially right angular formation, being bent at right angles intermediate their ends in order that the enlarged hollow base portions, 6 thereof may be flushly engaged with the desired portions of the crown-sheet 2, while the percolators 5 are slightly offset intermediate their ends, as at 8, in directions opposite to each other, whereby the same will be provided with an uninterrupted vertical path between the adjacent horizontal fire-tubes 3.

Horizontal plates 9 and 10 are arranged in the boiler casing in spaced superposed relation, the baffle 9 being rigidly secured in position at a point in proximity to the top of the boiler casing by flanging the ends thereof, as at 11, and passing bolts 12 therethrough into engagement with adjacent portions of the headers of said boiler, while the baffle 10 is arranged below the baffle 9 and is in turn, rigidly secured in such position by connection with the vertical tubular portions of the percolators 4 and 5 in passing therethrough. A plurality of openings 13 are formed in the baffle plate 9, at points laterally of the discharge ends of the various percolators 4 and 5, serving as ports for permitting the passage of steam generated in the boiler to the dome 14 thereof. Other openings 15 are formed in the baffle 10 and

serve for a purpose similar to the openings 13, while in addition to these openings 15, said plate 10 is provided with a plurality of parallel longitudinally extending grooves 5 or troughs 16, having openings 17 formed in the bottoms thereof to permit the escape of water. In this particular connection, it is well to note that the various perforated troughs 16 are arranged in vertical alinement 10 with the particular fire-tubes 3 below the same, and by consequence, water passing from the opening 17 thereof will contact with said fire-tubes for a purpose which will be presently described.

15 The operation of my improved boiler may be reviewed as follows:

Assuming that the boiler 1 has been supplied with the necessary amount of water, reaching the heights 5 indicated in the Fig.

20 2, the heat radiated from the fire-box thereof will serve to effect circulation of such water and with its gradual increase in temperature, a percolating action will ensue, that is, the water when heated to the proper 25 degree, will circulate as a body and a portion thereof will enter at openings or ports formed in the enlarged hollow bases 6 of each of the percolating devices 4 and 5 and will rise in such percolating devices and 30 distribute from the upper ends thereof in form of fine streams or jets onto the uppermost baffle plate 9. At this time, the jets or streams of water will be broken up and distributed onto the uppermost of the super- 35 heated horizontal fire-tubes 3. By reason of the finely divided state of the water contacting with these superheated fire-tubes 3, it will be understood that the same, or at least a major portion thereof will be rapidly 40 converted into steam, such steam passing off from the boiler by way of the openings 13 in the baffle plate 9 to the steam dome 14. Such water as is not converted into steam or as is formed by condensation, will drain onto 45 the lower baffle plate 10 and will ultimately be received in the longitudinal trough 16 formed therein. From said troughs 16, the water will pass by way of the escape ports 17 onto those fire-tubes 3 directly below the 50 same and in this way, the remainder of the water circulated by the percolators 4 and 5 will be rapidly converted into steam for upward passage through the ports 15 in the baffle plate 10 and the ports 13 in the baffle 55 plate 9 into the steam dome 14 for subsequent use, as may be desired. Through the operation of the percolating devices 4 and 5, it is obvious that those horizontal fire-tubes 3 disposed above the normal water line in 60 the boiler will provide an effectual flashing device, which will reduce water contacting therewith to steam and if subjected to sufficient heat, will function to superheat such steam, thus producing what is commonly known in the art as dry steam.

Instead of employing my invention with the type of fire-box as shown in the drawings herewith, it is to be appreciated that the invention may be equally well adapted for use in connection with various other types of fire-boxes, as for illustration, those types which are provided with flat or irregular crowns. Furthermore, boilers provided with the invention need not be of a size corresponding to those types of boilers employed at the present time, and also by means of the improved method of circulation, a materially less quantity of water may be used with success therein.

Manifestly, the construction shown is capable of considerable modification and such modification as is within the scope of my claims, I consider is within the spirit of my invention.

I claim:

1. In combination with a fire tube boiler having its normal water level at a point below a portion of the fire-tubes thereof, percolating means in the boiler for circulating the water, spaced superposed internal baffles extending throughout the boiler, one of said baffles being arranged to have jets of water from said percolating means impinged thereupon and distributed over the uppermost of said fire-tubes, and the other of said baffles having means for receiving the unconverted water from said jets and distributing the same by gravity over the remainder of the fire-tubes.

2. In combination with a fire tube boiler having its normal water level at a point below a portion of the fire-tubes thereof, percolating means for circulating the water in said boiler, spaced superposed internal baffles extending throughout the boiler, one of said baffles being arranged to have jets of water from the percolating means impinged thereupon for distribution over the uppermost of the fire-tubes and openings therein for permitting the escape of steam generated to the dome of the boiler, and the other of said baffles, having means for receiving the unconverted water from said percolating means and directing the same onto the remainder of the fire-tubes.

3. In combination with a fire tube boiler having its normal water level at a point below a portion of the fire-tubes thereof, percolating devices for circulating the water in said boiler comprising hollow elongated tubular members having enlarged perforated hollow bases arranged adjacent the crown-sheet of the boiler fire-box, spaced superposed internal baffles extending throughout the boiler, one of said baffles being arranged to have jets of water from the percolating devices impinged thereupon for distribution over the uppermost of the fire-tubes, and the other of said baffles having means for receiving the unconverted water from the perco-

lating devices and distributing the same by gravity over the remainder of said fire-tubes.

4. In combination with a fire tube boiler having a plurality of horizontal fire-tubes 5 therein and its normal water level at a point below a portion of said fire-tubes, percolating devices for circulating water in said boilers consisting of elongated tubular members having enlarged perforated bases positioned 10 adjacent and secured to portions of the crown-sheet of the boiler fire-box, the tubular portions of said percolating devices extending upwardly between the fire-tubes, spaced horizontal internal baffles in the 15 boiler, one of said baffles being arranged to have jets of water from the percolating devices impinged thereupon and also having steam escape ports therein, and the other of 20 said baffles being formed with means for receiving the unconverted water from said percolating devices and directing the same by gravity onto the remainder of the fire- 25 tubes.

5. In combination with a fire tube boiler 25 having a plurality of horizontal fire-tubes

therein and its normal water level arranged below a portion of such tubes, percolating devices for circulating water in said boiler comprising upright elongated tubular members 30 for enlarged perforated bases secured to adjacent portions of the crown-sheet of the boiler fire-box, spaced superposed internal baffles in the boiler, one of said baffles being arranged to have jets of water from the percolating devices impinged thereupon 35 for subsequent distribution over the uppermost of said fire-tubes and also having steam escape openings therein, and the other of 40 said baffles having a plurality of steam escape openings and a plurality of longitudinally disposed perforated troughs therein for receiving the unconverted water from 45 said percolating devices, said troughs being arranged in vertical alinement with the fire-tubes therebelow whereby to direct such unconverted water onto said last fire-tubes before conversion into steam.

In witness whereof I have hereunto set my hand.

GEORGE S. ROBERTS.
